UNITED STATES PATENT OFFICE.

WILLIAM E. LEE, OF COLUMBUS, OHIO.

DESIGN FOR A WIND-WHEEL.

51,235.

Specification for Design.

Patented Sept. 4, 1917.

Application filed July 5, 1917. Serial No. 178,876. Term of patent 3½ years.

To all whom it may concern:

Be it known that I, WILLIAM E. LEE, a citizen of the United States, residing at Columbus, in the county of Franklin and State of Ohio, have invented a new, original, and ornamental Design for Wind-Wheels, of which the following is a specification, reference being had to the accompanying drawing, forming part thereof.

Figure 1 is a top plan view, and Fig. 2 is a side elevation of a wind-wheel showing my new design.

I claim:

The ornamental design for a wind wheel, as shown.

WILLIAM E. LEE.
